GARDEN HOSE GUIDE

Roy H. Rogers, 7739 Bothwell Road,
Reseda, Calif. 91335

Filed Dec. 16, 1968, Ser. No. 14,984

Term of patent 14 years

Int. Cl. D6—01

U.S. Cl. D33—17

FIG. 1 is a perspective view of a garden hose guide showing my new design;

FIG. 2 is an elevational view thereof;

FIG. 3 is a top plan view thereof; and

FIG. 4 is a bottom plan view thereof.

I claim:

The ornamental design for a garden hose guide, as shown.
